COLLAPSIBLE MOLD

Claude G. Richards, Rosendale, Mo.

Application October 8, 1931, Serial No. 567,707

7 Claims. (Cl. 25—128)

My invention relates to molds for forming concrete pipe or tile.

A primary object of the invention is to provide a collapsible mold comprising inner and outer forming members which may be readily assembled and disassembled with a minimum of labor and strain upon the parts.

Another object of the invention is to provide a collapsible inner form or barrel comprising hinged sections and a single operating and lifting rod therefor and which rod incorporates a combined guide and supporting bracket providing a hinge connection between certain mold sections, there being means on the rod cooperable with the bracket whereby the mold sections may be lifted through the bracket; or through the bracket and rod-carried mold section operating means.

Another object of the invention is to provide a retractile filler plate between the free edges of the hinged barrel sections and to so connect the retractile filler plate and hinged barrel sections that, regardless of the size of the mold, the barrel may be placed in and automatically removed from molding position by merely attaching the operating and lifting rod to a suitable crane or hoist.

A further object of the invention is to provide improved and simplified means for forming the bell end of the tile or pipe.

A still further object of the invention is to provide a sectional outer mold member with improved means for quickly and easily connecting and disconnecting the sections.

A still further object of the invention is to provide a mold which may be used with equal facility in forming the tile or pipe, either bell end up or bell end down depending on the desire of the operator.

Other objects and advantages of the invention not specifically pointed out above will become apparent during the course of the following detailed description, when read in conjunction with the accompanying drawings which form a part of this specification and in which;

Figure 1 is a perspective view showing the molding ring;

Figure 2 is a central vertical sectional view, showing the parts in molding position;

Figure 3 is an enlarged detailed sectional view taken on the line 3—3 of Figure 1;

Figure 4 is an enlarged detailed sectional view taken on the line 4—4 of Figure 2;

Figure 5 is a sectional view taken on the line 5—5 of Figure 2.

Figure 6 is a partial sectional view of a slightly modified form of the invention employed in molding the tile with the bell end down;

Fig. 7 is a perspective view of the outer form; and

Fig. 8 is a perspective view of the collapsible core.

Referring now to the drawings in detail, where-in like numerals refer to like parts through out the same, 10 indicates the outer mold form which is formed of two semi-cylindrical sections 11 and 12. Angle irons 13 and 14 secured to the vertical edges of the respective sections 11 and 12 prevent said edges from becoming deformed and also afford a means of joining the two sections together. A plurality of spaced L-shaped straps are hingedly secured at one end as at 16 to the section 12 so that when the sections are placed in mating relation, the straps may be swung to the position shown in Figure 3 to dispose the other end 17 of said strap across the outer edges of the angle bars 13 and 14. The bars 13 and 14, and thus the mold sections, are drawn together through the medium of cam elements 18 which are rotatably mounted as at 19 on the ends 17 of the straps 15. Each of the cam elements 18 is formed with an integral operating handle 20.

A horizontally disposed semi-circular angle iron 21 is riveted as at 22 to each of the mold sections 11 and 12, the purpose of said angle irons being to form a strengthening ring to add rigidity to the mold and prevent deformation of the sections thereof. The mold 10 is enlarged at one end as at 23 to provide for forming the bell end of the concrete tile.

The core or barrel 24, which is of course of lesser diameter than the outer form 10, is formed of two substantially semi-cylindrical sections 25 and 26 which are hingedly connected along one vertical edge through the medium of suitable hinges 27 secured to the inner faces thereof. While the sections 25 and 26 are cylindrical in contour, they are formed so that when expanded to form a true cylinder, an appreciable space is left between the free edges thereof. This space is closed during the molding operation by a retractile filler plate 28 having a contour conforming to that of the sections 25 and 26. It will be noted that the edges of the sections and of the plate 28 are beveled inwardly to facilitate movement of the plate into and out of operative position.

The core is controlled entirely through the medium of a centrally disposed reciprocable operat-

ing rod 29 which is slidably mounted in vertically aligned eyes 30 of horizontal bracket arms 31 mounted upon the pintles 32 of the hinges 21. A pair of braces 33 extending between the arms 31 serve to hold the eyes 30 in correctly spaced relation so as to prevent binding against the rod 29. As will be developed later, the brackets 31 acting through rod 29 also constitute a sustaining support for the sections 25, 26 when the same are collapsed and lifted or lowered by rod 29.

10 are collapsed and fitted on 11. A pair of vertically spaced collars 34 are slidably mounted upon the rod 29 intermediate of the eyes 30 and are formed with pairs of oppositely directed ears 35 between which the inner ends of a pair of oppositely directed radial arms 36 are pivoted as at 37. The outer ends of the radial arms 36 are pivotally connected through the medium of a suitable U-coupling to the inner surfaces of the respective core sections 25 and 26 intermediate the vertical edges thereof.

20 25 and 26 intermediate the vertical edges thereof.
Movement of the collars 34 on the rod 29 is limited by suitable stop pins 39 so that it will be evident that movement of the rod 29 upwardly will result in drawing the sections 25 and 26 together to collapse the core and movement of the rod downwardly will result in movement of the sections to expanded position.

the sections to expanded position.

The retractible filler plate 28 is mounted upon a channel-shaped member 40 which is considerably wider than the plate 28 so as to contact the inner surface of the sections 25 and 26 and thus insure correct alinement of the plate 28 with said sections. The member 40 is pivotally connected at 41 to a pair of spaced U-shaped members 42 which are rigidly secured as at 43 to a pair of spaced radial arms 44. The arms 44 are in turn pivotally secured as at 45 between spaced ears 46 formed with collars 47 which are mounted fast upon the rod 29, being held from axial movement thereon by means of pins 48. Suitable curved guide fingers 49 are mounted on the inner surface of the sections 25 and 26 adjacent the free vertical edges thereof to insure that the plate 29 will always be moved into expanded position in correct alinement.

45 in correct alinement.
It will be evident that upon movement of the rod 29 up and down to collapse and expand the core 24, the filler plate 28 will also be moved out of and into operative position. Due to the slight relative movement permitted between the rod 29 and the collars 34, the filler member will always be slightly retracted before the core starts to collapse and the core will always be fully expanded before the filler is forced into final operative position.

55   The spacing of the parts of the core is such that when the core is fully collapsed, the uppermost pin 48 engages the uppermost eye 30, thereby taking the strain off of the sides of the core when the same is lifted. In other words the lifting force is applied to the sections 25, 26 by brackets 31 at the site of hinges 32 and also at the points of attachment of the toggle arms or levers 36 which are, as shown, removed forty five degrees, more or less from hinges 32. This construction is very important because it distributes the lifting stresses and prevents warping of the sections 25, 26 and likewise undue strain on the rod 29, brackets 31 and levers 36. Of course in the embodiment shown, the first upward movement of rod 29 retracts section 28, whereupon continued upward movement of rod 29 collapses sections 25, 26 against one another as shown in Figure 8; and then the uppermost pin 48 engages eye 30 of bracket 31, whereupon the

core section of the mold is lifted by rod 29 through brackets 31 and levers 36 as indicated.

In order to form the inner contour of the bell end of the tile, an angular in cross section circular ring 50 is provided. The ring 50 is of an external diameter slightly larger than the internal diameter of the mold 10 and rests upon the upper end of the core 24, being held in concentric relation thereto by means of spring fingers 51 carried by said ring and engaging the inner surface of said core. In order to facilitate removal of the ring 50 after the tile is formed, the ring is obliquely split as at 52. A hand lever 53 is pivotally connected as at 54 and 55 to the ends of said ring so that upon movement of said lever about the pivot 54, the pivot 55 will be raised to contract the ring.

contract the ring.

In the operation of the mold, the outer members 11 and 12 are joined together and the core member is lowered into position and expanded, 20 the bell forming ring is then mounted upon the core and the concrete or other plastic material 56 is poured to fill the mold. After the concrete has set, the ring 58 is first removed and then the core is lifted out by attaching a crane or hoist to the upper end of the rod 29. Raising of the rod 29 collapses the core thus freeing the same from the tile and the core may then be removed by continued lifting of the rod. The outer mold 10 may then be removed by releasing the cam locks 18 and separating the sections 11 and 12. 30

In the modified form of the invention shown in Figure 6, a mold is shown for casting tile with the bell end down. The mold in this form of the invention is identical with that above described except that the bell forming ring 51 is formed with fingers 58 which engage the outer surface of the core 24. This change in the construction of the bell forming ring is necessitated due to the fact that when the tile is cast with the bell end down, the core will have to be removed before the ring. Otherwise the operation of this form of the invention is the same as the first described form.

While a preferred embodiment of the invention has been shown and described, it will be understood that various changes in the details of construction may be resorted to without departing from the spirit of the invention as defined by the appended claims. 45 50

I claim:

1. A core member for a conduit mold or the
like comprising a pair of major sections, hinge
means connecting said major sections at one lon-
gitudinal edge of same, a minor mold section 55
substantially coextensive in length with said
major sections, inwardly extending brackets car-
ried by said hinge means and having aligned
bearings in their inner ends, a pull rod slidably
carried in said bearings and providing means
for attachment to a hoist, a pair of pivot-carry-
ing ears fast on said pull rod, a pair of levers
pivoted at their inner ends in said respective
ears and having their outer ends pivoted to said
minor mold section, whereby to positively ac-
tuate said minor section inwardly and outwardly
according to the direction of movement of said
pull rod in said bearings, such actuation of the
minor section taking place immediately the pull
rod is moved; a pair of collars slidable on said
pull rod and each providing a toggle arm actuat-
ing connection with said major mold sections,
stops on said rod and spaced to engage said col-
lars after predetermined free movement of the
rod there through whereby to effect movement 70

- of the major mold sections after movement of the minor mold section; shoulder means on said pull rod and engaging one of said bracket bearings when the mold sections are collapsed with their 5 free ends in contact and the minor section housed therein whereby to effect lifting of said core member through said hinge carrying bracket and through the toggle arm actuating connections upon further upward movement of said pull rod; 10 fingers on said major sections adjacent their free edges for guiding the minor section to and from operative position, and means for maintaining said minor section between said fingers.
2. The combination set forth in claim 1, and 15 the means for maintaining the minor section between said fingers comprising a prop arm on one of said minor section levers and arranged to engage said minor section.
3. The combination set forth in claim 1, and 20 combined brace and tie means connecting said brackets.
4. In a mold core including a pair of major sections and a minor section upon which the major sections are adapted to close; the combination of bracket members, hinge means carrying 25 said bracket members and connecting said major sections along one longitudinal edge whereby said major sections can be actuated to complete disengagement from the work, aligned bearings adjacent the inner ends of said bracket members, an actuator rod in said bearings, means on said 30 actuator rod and operatively connected to said minor section for actuating the same immediately the rod is moved, stops on said actuator rod, and collar-carried toggle-like supports for said 35 major sections and slidably on said rod between said stops whereby the major sections will not be actuated until the minor section has been actuated to or from its operative position according to the direction of movement of the actuator rod in said bearings.
5. The combination set forth in claim 4 and including a second stop on said actuator rod and arranged to engage one of said bracket bearings after said major sections have been collapsed against one another following withdrawal of the minor section from operative position, whereby said bracket members cooperate with said rod and toggle-like major section supports for raising the collapsed core. 10
6. In a core mold having its major part providing inwardly and outwardly swingable opposed edge portions adapted to seat against a minor section which is mounted for movement to and 15 from operative position; the combination of inwardly and laterally extending guide fingers carried by said mold adjacent said edge portions for guiding said minor section to and from operative position, and means independent of said outwardly swingable portions for confining said minor section between said guide fingers at all times. 20
7. In a core mold having its major part providing inwardly and outwardly swingable opposed edge portions adapted to seat against a minor section which is mounted for movement to and from operative position; the combination of inwardly and laterally extending guide fingers carried by 25 said major part of the mold adjacent said edge portions for guiding said minor section to and from operative position, a combined operating lever and support means for said minor section for moving it to and from operative position, and a stop on said lever and support means adapted 30 to engage the rear face of said minor section to limit rearward movement of same whereby to 35 maintain it between said guide fingers. 30

CLAUDE G. RICHARDS.
